UNITED STATES PATENT OFFICE

159,587

COMBINED BROOCH AND WATCHCASE

Marcel Boucher, Staten Island, N. Y.

Application November 25, 1949, Serial No. 6,241

Term of patent 3½ years

(Cl. D45—19)

To all whom it may concern:

Be it known that I, Marcel Boucher, a citizen of the United States, residing in New York city, in the county of Richmond and State of New York, have invented a new, original, and ornamental Design for a Combined Brooch and Watchcase, of which the following is a specification, reference being had to the accompanying drawing, forming part thereof.

Fig. 1 is a front elevational view of a combined brooch and watchcase, showing my design, and Fig. 2 is the side view thereof.

I claim:

The ornamental design for a combined brooch and watchcase, substantially as shown.

MARCEL BOUCHER.
